Seldon Spencer Ridenour, Rock Island, Ill., assignor to Fairbanks, Morse & Co., Chicago, Ill., a corporation of Illinois

Application January 5, 1953, Serial No. 23,006

Term of patent 14 years

(Cl. D52—10)

To all whom it may concern:

Be it known that I, Seldon Spencer Ridenour, a citizen of the United States, residing at Rock Island, county of Rock Island, State of Illinois, have invented a new, original, and ornamental Design for a Combined Weight Indicator and Recorder, of which the following is a specification, reference being had to the accompanying drawings, forming a part hereof.

In the drawings:

Fig. 1 is a top plan view of a combined weight indicator and recorder embodying my new design;

Fig. 2 is a front view of the combined weight indicator and recorder;

Fig. 3 is a side elevational view of the left hand side of the combined weight indicator and recorder as viewed in Fig. 2;

Fig. 4 is a side elevational view of the right hand side of the combined weight indicator and recorder as viewed in Fig. 2; and

Fig. 5 is an isometric view of the combined weight indicator and recorder.

I claim:

The ornamental design for a combined weight indicator and recorder, as shown.
